CLAIM

The ornamental design for a combined light bulb attachment and supported scent releasing pebbles therefor, as shown and described.

DESCRIPTION

FIG. 1 is a top perspective view of a combined light bulb attachment and scent releasing pebbles therefor showing my new design, the light bulb being shown in broken lines for illustration purposes only;

FIG. 2 is a top plan view thereof on an enlarged scale;
FIG. 3 is a side elevational view thereof on an enlarged scale, the opposite side of the attachment being a mirror image;

FIG. 4 is an end elevational view thereof on an enlarged scale, the opposite end of the attachment being a mirror image;

FIG. 5 is a bottom plan view thereof on an enlarged scale..
